UNITED STATES PATENT OFFICE

2,341,022

GRINDING WHEEL FORM DRESSER

William F. Dalzen, Grosse Pointe, Mich.

Original application April 19, 1941, Serial No. 389,263, now Patent No. 2,277,213, dated March 24, 1942. Divided and this application December 18, 1941, Serial No. 423,517

12 Claims. (Cl. 125—11)

This invention relates to a grinding wheel form dresser, and more particularly to a dresser of this type adapted for use in conjunction with a thread grinding machine, wherein a work-piece is rotated and reciprocated on a suitable carriage past a rotatable abrasive grinding wheel with the cutting peripheral edge thereof cooperatively engaging transversely the surface of the work-piece for grinding a thread in the same.

From time to time the cutting edge of the grinding wheel is worn down, or is broken, or chipped requiring a re-truing or resurfacing. Or on the other hand it may be desired to vary the shape or angle of the sides of the peripheral grinding edge thereof. The grinding wheel form dresser hereinafter described in detail is therefore adapted for accomplishing the above purposes.

It is the object of this invention to provide a novel grinding wheel form dresser adapted to produce various shaped surfaces in the edge of the abrasive grinding wheel for accurately grinding out various shapes of threads.

It is the further object of this invention to provide a manually actuatable form dresser with a plurality of diamond mountings for cooperatively engaging the opposite edges of the grinding wheel periphery when the latter is dressed.

It is the further object of this invention to provide a plurality of simultaneously manually actuated diamond mounting means whereby said mountings may be brought to bear upon opposite edges of the grinding wheel at the same time.

It is the still further object herein to provide means for maintaining the reciprocable diamond mounting supports entirely dust-free.

It is the further object herein to provide means for adjusting the angular inclination of the diamond mountings whereby a plurality of angles may be dressed in the peripheral edges of the grinding wheel.

It is the still further object herein to provide an auxiliary mechanism in conjunction with said form dresser for dressing the outer edge of the abrasive grinding wheel for providing thereon a curved surface, together with adjusting means for regulating the degree of curvature.

Other objects will be seen in the various arrangements of parts and combinations thereof as will be hereinafter described in connection with the appended drawings of which:

Figure 1 is a top plan view of the grinding wheel dresser.

Figure 2 is an elevational view of the same.

Figure 3 is a left end view thereof.

Figure 4 is a partially sectioned elevational view of the diamond mounting and adjusting means for said grinding wheel dresser.

The above drawings illustrate merely preferable embodiments of the invention, it being expressly understood that it is not intended that the invention be limited thereby.

In the drawings, a grinding wheel dresser is generally indicated as A with its housing 11 vertically and reciprocably mounted within the support 12 with friction minimizing ball races or ways 13 interposed therebetween. Support 12 is joined to the vertically movable grinding wheel support or housing 14 and is adapted to move therewith.

Lever 21 has a lug on its end adapted to support the housing 11 of the dressing mechanism A at point 22. Said housing while resting upon the end of lever 21 is longitudinally and reciprocably disposed within the vertical support 12. Said lever 21 is centrally pivoted at point 23 to the movable housing 14 which provides a movable support for the pivot point 23.

The other end of the lever 21 also has a lug thereon for adjustable engagement with respect to the column 19 at point 19'. Said column being fragmentarily shown in Figure 2 but more fully shown in Figures 1, 2, 3, 7 of the drawings of application Serial No. 389,263, of which the instant application is a divisional part, as above more fully set out.

An adjustable relation is maintained between lever 21 and column 19 as the wheel supporting housing 14 is downwardly fed, whereby the dresser is permitted to properly engage the surface of the grinding wheel 20 in operative dressing position.

A compensating screw 21' is longitudinally disposed within a bracket member 21'' secured to the column 19. A washer 22' is secured upon the end of screw 21' by a nut 23'; and the end of lever 21 is beneath said washer at point 19' whereby a retaining means is provided preventing rotation of lever 21.

A calibrated nut 11' is threadably disposed on the lower end of the compensating screw 21' and thereby provides a manually operable adjusting means permitting longitudinal adjustment of the compensating screw 21' whereby the lever 21 is correspondingly adjusted as desired.

The above dressing mechanism is a form dresser adapted to obtain a plurality of angles and shapes in the peripheral edge on the abrasive grinding wheel 20 depending upon the form of thread desired.

By utilizing the support 12 as illustrated in

Figures 1 and 2, and the ball races or ways 13 it is seen that dresser A is easily removable and interchangeable with any other type of dresser mechanism if desired.

Referring to Figures 1 through 4, the dresser housing 11 has a pair of angularly adjustable members 97 and 98, one of which is shown in sectioned detail in Figure 4. Said member has oppositely disposed hollow cylindrical portions 99, within the ends of which are inserted the hollow flanged sleeve bearing members 100 and 101.

The shaft 102 is reciprocably mounted within cylindrical members 99 and said bearing members, and has secured thereto a hollow diamond housing support 103. Said support is formed with annular cylindrical projections 104 and 105 disposed in spaced relation to the reciprocable shaft 102. An annular cylindrical member 106 is joined to bearing member 101 providing a space therebetween for slidably receiving the cylindrical projection 104 of the diamond mounting support 103.

The principal purpose of projections 104 and 105 and the cylindrical member 106 is for closing off shaft 102 from the atmosphere, preventing dust from getting in. The shafts 102 are further kept dust-free by means of the caps 102' removably secured within the ends of bearing members 100 and 101.

It will be noted in this connection that it is absolutely essential that the reciprocable shafts 102 be kept dust-free, and by the above mechanism this result is guaranteed.

A diamond mounting 107 is secured within support 103, with the end of said mounting adapted to engage the peripheral edge of the grinding wheel 20 as best seen in Figure 2.

It will be understood that a similar mounting is disposed within the member 98 for cooperatively engaging the other side of the peripheral edge of said grinding wheel.

When inoperative the diamond mountings are supported above and out of contact with the grinding wheel 20; and are lowered for engagement therewith when a dressing operation is desired. Said dressing operation is always from the top of the wheel with the result that the possibility of wheel breakage is eliminated.

For accomplishing the raising and lowering of said mountings a manually actuated handle 108 is employed, pivoted on its end at 109 to the dresser housing 11 through the intermediate supports 110 which are pivoted at their lower extremities to the rod 111.

A bifurcated stirrup 112 is pivoted at 113 to the handle 108 and is adapted for reciprocable movement therewith. A guide member 113 forming an integral part of pivotal shaft 115 transversely secured through the dresser housing 11, is slidably disposed within the stirrup 112 and provides a guide therefore.

A link 116 is pivoted at the lower extremity of said stirrup at point 117, with its other end pivotally joined to the diamond housing support 103 within the supporting member 98.

A similar link 118 is pivoted at 119 to stirrup 112 and is adapted to pivotally connect a similar diamond mounting support within the member 97, the detail of which is omitted in Figure 2 for purposes of simplicity.

Consequently by manipulation of handle 108 the diamond mounting supports 103 within their respective supporting members 97 and 98 may be reciprocated whereby the diamond mountings

107 on both sides of the grinding wheel may be brought into and out of engagement with said grinding wheel for permitting the dressing operation. It will be noted, however, that the dressing operation is accomplished on the downward motion of the diamond mounting 107.

It will be understood that various shapes and angles may be dressed in the peripheral edge of the grinding wheel. This is accomplished by providing an angular adjustment for members 97 and 98 which are pivotally supported within housing 11 at points 120 with suitable bolts being provided for angularly securing the same. Said members have an additional opening at points 121 through which are disposed bolts 122 carried in a suitable slot within housing 11, with nuts secured thereon for adjustment with respect to said housing.

For angularly adjusting members 97 and 98 screws 146 are threadably journaled within suitable brackets 147, the latter forming a part of housing 11 of the dressing mechanism.

Members 123 and 124 have oppositely disposed projections 148 which are cooperatively engaged by the heads of screws 146 and washers 149 secured upon said screws in spaced relation to said heads.

Consequently with connections 120 and 122 loosened, screws 146 may be manually adjusted for regulating the angular relation of the diamond mounting supports 103.

Members 123 and 124 are oppositely disposed in the top of the supports 97 and 98 and provide a means of measurement from an intermediate central point to guarantee that both supports are disposed at the same complementary angles with respect to the grinding wheel. So provisioned it is easily seen that both sides of the peripheral grinding wheel will be dressed at the same angle.

The central point above referred to though not included in the drawings may be arbitrarily marked upon the top edge of the housing 11 as desired.

Furthermore by said adjusting means the dressing angle may be varied as and when desired whereby the dresser A is adapted to dress a plurality of angles in the peripheral edge of a grinding wheel.

Referring to Figure 4 it is seen that the shaft 102 is split at its ends at points 125 where by means of suitable adjusting screws 126 the diameter on the ends of said shaft may be slightly increased for taking up wear of said shaft or bearing members 100 and 101.

Having described my invention reference should now be had to the claims which follow for determining the scope of this invention.

I claim:

1. A grinding wheel dresser comprised of a housing, a pair of angularly adjustable diamond mounting supports pivotally secured therein, each support having a pair of oppositely disposed hollow members integral therewith, hollow cylindrical bearing members disposed within said members, shafts slidably disposed within said bearing members, diamond mounting blocks joined to said shafts, with diamonds therein adapted to concurrently engage both peripheral edges of a grinding wheel, the opposite ends of said blocks having annular openings into which said bearing members extend, and a common manually actuated means joined to the said diamond mounting blocks for reciprocating the same and said shafts together in the same di-

rection within said bearing members toward and away from said wheel.

2. A grinding wheel dresser comprised of a housing, a pair of angularly adjustable diamond mounting supports pivotally secured therein, each support having a pair of oppositely disposed hollow members integral therewith, hollow cylindrical bearing members disposed within said members, shafts slidably disposed within said bearing members, diamond mounting blocks joined to said shafts, with diamonds therein adapted to concurrently engage both peripheral edges of a grinding wheel, the opposite ends of said blocks having annular openings into which said bearing members extend, a common manually actuated means joined to the said diamond mounting blocks for reciprocating the same and said shafts together in the same direction within said bearing members, and covering means for the outside ends of said bearing members, which together with said overlapping annular openings provide dust-free enclosures for said shafts.

3. A grinding wheel dresser comprised of a housing, a pair of angularly adjustable diamond mounting supports pivotally secured therein, each support having a pair of oppositely disposed hollow members integral therewith, shafts slidably disposed within said members, diamond mountings secured to said shafts, adapted to concurrently engage both peripheral edges of a grinding wheel, a common manually actuated means joined to said mountings for reciprocating the same, and said shafts together in the same direction within said hollow members, said shafts being split at their ends with corresponding threaded openings, and adjusting screw members within said openings.

4. A grinding wheel dresser comprised of a housing, a pair of angularly adjustable diamond mounting supports pivotally secured therein, each support having a pair of oppositely disposed hollow members integral therewith, shafts slidably disposed within said members, diamond mountings secured to said shafts, adapted to concurrently engage both peripheral edges of a grinding wheel, a common manually actuated means joined to said mountings for reciprocating the same and said shafts together in the same direction within said hollow members, oppositely projecting studs on said supports, and adjusting screw members threadably journaled on said housing joined to said studs for regulating the angular adjustment of said supports.

5. A grinding wheel dresser comprised of a housing, a pair of angularly adjustable diamond mounting supports pivotally secured therein, each support having a pair of oppositely disposed hollow members integral therewith, shafts slidably disposed within said members, diamond mountings secured to said shafts, adapted to concurrently engage both peripheral edges of a grinding wheel, a common manually actuated means joined to said mountings for reciprocating the same and said shafts together in the same direction within said hollow members, manually operable means in said housing joined to said supports for regulating the angular adjustment thereof, and inwardly projecting studs on said supports providing measuring means to an intermediate central point between said supports.

6. A grinding wheel dresser comprised of a housing, a pair of angularly adjustable diamond mounting supports pivotally secured therein, hollow cylindrical bearing members disposed within said supports, shafts slidably disposed within said

bearing members, diamond mounting blocks joined to said shafts, with diamonds therein adapted to concurrently engage both peripheral edges of a grinding wheel, the opposite ends of said blocks having annular openings into which said bearing members extend, and a common manually actuated means joined to the said diamond mounting blocks for reciprocating the same and said shafts together within said bearing members towards and away from said wheel in the same direction.

7. A grinding wheel dresser comprised of a housing, a pair of angularly adjustable diamond mounting supports pivotally secured therein, hollow cylindrical bearing members disposed within said supports, shafts slidably disposed within said bearing members, diamond mounting blocks joined to said shafts, with diamonds therein adapted to concurrently engage both peripheral edges of a grinding wheel, the opposite ends of said blocks having annular openings into which said bearing members extend, a common manually actuated means joined to the said diamond mounting blocks for reciprocating the same and said shafts together in the same direction within said bearing members, and covering means for the outside ends of said bearing members, which together with said overlapping annular openings provide dust-free enclosures for said shafts.

8. A grinding wheel dresser comprised of a housing, a pair of angularly adjustable diamond mounting supports pivotally secured therein, shafts slidably disposed within said supports, diamond mountings secured to said shafts, adapted to concurrently engage both peripheral edges of a grinding wheel, a common manually actuated means joined to said mountings for reciprocating the same, and said shafts together in the same direction within said supports, said shafts being split at their ends with corresponding threaded openings, and adjusting screw members within said openings.

9. A grinding wheel dresser comprised of a housing, a pair of angularly adjustable diamond mounting supports pivotally secured therein, shafts slidably disposed within said supports, diamond mountings secured to said shafts, adapted to concurrently engage both peripheral edges of a grinding wheel, a common manually actuated means joined to said mountings for reciprocating the same and said shafts together in the same direction within said supports, oppositely projecting studs on said supports, and adjusting screw members threadably journaled on said housing joined to said studs for regulating the angular adjustment of said supports.

10. A grinding wheel dresser comprised of a housing, a pair of angularly adjustable diamond mounting supports pivotally secured therein, shafts slidably disposed within said supports, diamond mountings secured to said shafts, adapted to concurrently engage both peripheral edges of a grinding wheel, a common manually actuated means joined to said mountings for reciprocating the same and said shafts together in the same direction within said supports, manually operable means in said housing joined to said supports for regulating the angular adjustment thereof, and inwardly projecting studs on said supports providing measuring means to an intermediate central point between said supports.

11. A grinding wheel dresser comprised of a housing, a pair of angularly adjustable diamond mounting supports pivotally secured therein, shafts slidably disposed within said supports,

diamond mountings secured to said shafts, adapted to concurrently engage both peripheral edges of a grinding wheel, manually operable means pivotally mounted above said housing, slotted operating means depending therefrom, oppositely disposed links joined to said operating means, and interconnecting said diamond mountings for reciprocating the same and said shafts together in the same direction within said supports towards and away from said wheel, said shafts being split at their ends with corresponding threaded openings, and adjusting screw members within said openings.

12. A grinding wheel dresser comprised of a housing, a pair of angularly adjustable diamond mounting supports pivotally secured therein, each support having a pair of oppositely dis-

posed hollow members at the ends thereof and integral therewith, shafts slidably disposed within said members, diamond mountings secured to said shafts, adapted to concurrently engage both peripheral edges of a grinding wheel, manually operable means pivotally mounted above said housing, slotted operating means depending therefrom, oppositely disposed links joined to said operating means, and interconnecting said diamond mountings for reciprocating the same and said shafts together in the same direction within said hollow members towards and away from said wheel, and means transversely disposed within said housing and the slot in said operating means for limiting lateral translation thereof.

WILLIAM F. DALZEN.
